UNITED STATES PATENT OFFICE.

WENCESLAUS F. MIKOLASEK, OF VODNANY, SOUTH DAKOTA.

PRAIRIE FIRE-FIGHTER.

No. 903,394.

Specification of Letters Patent.

Patented Nov. 10, 1908.

Application filed February 4, 1908. Serial No. 414,257.

To all whom it may concern:

Be it known that I, WENCESLAUS F. MIKOLASEK, citizen of the United States, residing at Vodnany, in the county of Bonhomme and State of South Dakota, have invented certain new and useful Improvements in Prairie-Fire Fighters, of which the following is a specification.

The object of this invention is an improved apparatus for use in fighting prairie fires, the invention embodying a preferably self-propelled vehicle or truck arranged to travel across a prairie or field and burn a strip or zone, the apparatus being provided with means for extinguishing the flame along the fired strip immediately, and preventing the communication of the fire to the other parts of the fields.

With these and other objects in view as will more fully appear as the description proceeds, the invention consists in certain constructions and arrangements of the parts that I shall hereinafter fully describe and claim.

For a full understanding of the invention, reference is to be had to the following description and accompanying drawings, in which:

Figure 1 is a side elevation of my improved fire fighting apparatus, parts being broken away; Fig. 2 is a top plan view thereof; Fig. 3 is a similar view of a modification. Fig. 4 is a detail sectional view illustrating the brushes at the side of the apparatus; Fig. 5 is a bottom plan view illustrating the preferred staggered or alternating arrangement of the brushes. Fig. 6 is a transverse sectional view through a portion of the vehicle and through the fire fighting apparatus carried thereby, and Fig. 7 is a side elevation of the fire fighting apparatus, a portion thereof being shown in section to more clearly illustrate the arrangement of the brushes used to extinguish the fire.

Corresponding and like parts are referred to in the following description and indicated in all the views of the drawings by the same reference characters.

My improved fire fighting truck embodies a body portion 1, front axle 2 supported on the front traveling wheels 3 and rear axle 4 with its traveling wheels 5. A prime mover 6 which may be a gasolene or other engine, is mounted on the body portion 1, preferably near the rear end thereof, and the driving

shaft 7 of the engine carries a sprocket wheel 8 which is connected by a sprocket chain 9 to a similar wheel 10 on the countershaft 11 extending transversely underneath the body portion 1 of the truck and journaled in suitable hangers. At its ends, the countershaft 11 carries spur pinions 12 which mesh with gear wheels 13 on the rear axle 4, so as to turn the axle and rear traveling wheels 5 in a direction to propel the truck forwardly.

The truck may be guided to the right or to the left by means of a steering rod 14 which carries the steering wheel 15 at its rear end and which extends forwardly down through the body portion 1 of the truck and is provided at its lower forward end with a worm 16 meshing with a worm gear 17. This worm gear 17 is secured on a transversely extending shaft 18 supported underneath the body portion 1 of the vehicle, and steering cables or chains 19 wind in respectively different directions on the shaft 18 and are connected to the front axle 2 near the ends thereof, so that as said shaft is rotated in one direction or the other through the instrumentality of the worm gearing and steering rod 14, one of the cables will wind up on the shaft and the other unwind therefrom so as to turn the vehicle to the right or to the left.

A reservoir 20 for liquid fuel, such as gasolene or other hydrocarbons, is mounted on the front end of the body portion 1 of the truck and an air pump 21 is also mounted on said body portion in juxtaposition to the reservoir 20, the said air pump being provided with a pipe 22 connected to the reservoir so as to feed air therein, said pipe 22 being provided with an ordinary check valve or other valve, as desired.

In one embodiment of the invention, a single fuel supply pipe 23 is secured at one end in the top of the reservoir 20 and extends outwardly therefrom and down along one side of the truck to the ground, said supply pipe being provided at its lower outer end with a laterally extending attenuated nozzle 24 formed with a series of jet orifices as shown, and carrying an igniting pan 25. Preferably as clearly illustrated in Fig. 2, the nozzle 24 is connected to the main portion 105 of the supply pipe 23 by a two-way joint 26, so that the nozzle may be turned upwardly towards the vehicle to pass over obstructions as the apparatus advances. The pipe 23 is provided with a globe or other form of valve 110

27 so that the liquid fuel may be allowed to flow from the reservoir to the nozzle 24 after the nozzle has been properly heated by the ignition of gasoline or the like in the pan 25, 5 the fuel being forced through the pipe 23 by the air pressure supplied by the pump 21 and the gaseous fuel formed passing out through the rearwardly opening jet orifices in the nozzle to set fire to the grass as the machine 10 travels along the prairie.

In order to prevent the flames from being communicated to the grass in front of the vehicle or apparatus, and starting forwardly therefrom without control, a roller 28 is 15 mounted in front of the nozzle 24 and is designed to travel along the ground. To confine the flame or burned area to a strip or zone of sufficient width to effectively fight the prairie fire and at the same time to protect 20 the vehicle and its operator from the flames, I provide an asbestos or other curtain 29 which in the present embodiment of the invention illustrated in Fig. 1, is, like the fire fighting apparatus, supported entirely upon 25 one side of the vehicle. This asbestos curtain 29 is of an extent laterally to encompass the nozzle 24 and is preferably supported from the right hand side of the body portion 1 of the truck by means of lateral braces 30 30 and an angular rear brace 31. The curtain is carried by a rectangular framework 32 to which the outer ends of the brace rods are connected, and the entire curtain with its framework and other correlated parts may 35 be swung upwardly and carried in a suspended relation in order to pass over obstructions, or to travel quickly to the proper point of vantage in fighting the fire, by means of a cable 33 which is secured to the 40 outer side of the curtain framework 32 and is mounted to wind upon a winch or hoisting drum 34 supported upon the body portion 1 of the truck.

The extent of the asbestos or other protective curtain 29, longitudinally considered, 45 may be varied according to judgment, but in any event should be of sufficient length to permit the grass to be thoroughly consumed after it has been lighted by the nozzle 24, before the flames are extinguished by the 50 brushes secured to the rear end of the apparatus.

In the preferred arrangement of the parts, I provide a transversely extending series of 55 extinguishing brushes and two longitudinally extending series of extinguishing brushes, as clearly illustrated in the drawing. Preferably the rear transversely extending series of brushes are arranged in two sets with two 60 rows of brushes to the set, the individual brushes, designated 35 are guided for a vertical movement and are pressed downwardly by means of springs 36 so as to effectively wipe into any depressions or uneven surfaces 65 faces along the ground as the vehicle ad-

vances so as to completely extinguish the fire. The side brushes 37 are similarly spring pressed, but are arranged in a single row, as shown, while the rear brushes of the two sets are mounted in an alternating arrangement, so as to leave no space on the ground where a brush will not act. The rear brushes 35 preferably run on the traveling rollers 38. In that form of the invention illustrated in Fig. 3, it will be seen that my 75 invention may also include a plurality of nozzles 24^a, two of them extending laterally on opposite sides of the vehicle, and the third extending along the rear end of the vehicle, and in transverse directions, the fire zone 80 with such an arrangement of parts being obviously, considerably wider than with the arrangement above described. In this modification or amplification of the invention, the rear brushes 35^a are employed similar to the 85 brushes 35, except that only one set of rear brushes is shown extending from side to side of the fire fighting apparatus and mounted on the traveling wheels 38^a. The front rollers 28^a similar to the rollers 28 are also provided 90 as shown, and in addition thereto is a third protective roller designated 28^b and mounted in front of the rearwardly disposed nozzle. In this form of the invention, an asbestos 95 curtain is provided to protect the vehicle 95 from the flames and the outlying portions from being fired, the said curtain being supported on the framework 32^a including any desired construction and arrangement of supporting rods 30^a and brace rods 39.

In the practical operation of my improved fire fighting apparatus, the machine is advanced along the prairie in the proper direction to most successfully cope with the oncoming fire, and the grass along a predetermined strip or zone is fired by the flames from the nozzles 24 or 24^a, as the case may be. All outlying portions of the grass are protected by the curtain and side and rear brushes, the said brushes effectively putting out the 110 fire on the fired portions or strip of grass, so that the fired or burned area will check the oncoming fire and prevent it from spreading beyond said area or zone, the invention clearly keeping the purposely started fire under control and within bounds.

Having thus described the invention, what is claimed as new is:

1. In an apparatus of the character described, the combination of a supporting vehicle, a grass firing apparatus carried thereby, and means for automatically extinguishing the fired grass, said extinguishing means being also supported by the vehicle.
2. In an apparatus of the character described, the combination of a grass firing apparatus, means for conveying the same along the fields to ignite the grass, and mechanical means for subsequently extinguishing the fire.

3. In an apparatus of the character described, the combination of a supporting vehicle, a fire nozzle carried thereby, means for supplying fuel to said nozzle, and extinguishing brushes carried by the vehicle in the rear of said nozzle.
4. In an apparatus of the character described, the combination of a supporting vehicle, a fire nozzle carried thereby, means for supplying fuel to the said nozzle, and vertically yieldable extinguishing brushes carried by said vehicle in the rear of said nozzle.
5. An apparatus of the character described, comprising a supporting vehicle, a firing nozzle carried thereby, means for supplying fuel to said nozzle, a transversely extending series of extinguishing brushes arranged to be trailed by said vehicle along the ground in the rear of said nozzle, and longitudinal rows of brushes extending from said nozzle to the first named brushes.
6. In an apparatus of the character described, the combination of a supporting vehicle, a fire nozzle carried thereby, means for

supplying fuel to said nozzle, and a ground roller mounted in front of said nozzle.

7. In an apparatus of the character described, the combination of a supporting vehicle, a firing nozzle carried thereby, means for supplying fuel to said nozzle, and a fire proof curtain also carried by said vehicle, the nozzle being located within the curtain.

8. In an apparatus of the character described, the combination of a supporting vehicle, a firing nozzle carried thereby and extending laterally therefrom and arranged to be raised and lowered towards or away from the vehicle, and an asbestos curtain supported by said vehicle, the nozzle being located within the curtain, and means mounted on the vehicle for raising the curtain.

In testimony whereof I affix my signature in presence of two witnesses.

WENCESLAUS F. MIKOLASEK.
